SHEET-FEEDING MECHANISM.

1,033,444.

Specification of Letters Patent.

Patented July 23, 1912.

Application filed July 11, 1908. Serial No. 443,053.

To all whom it may concern:

Be it known that L. Lewis E. Morrison, a citizen of the United States of America, and a resident of the city of Newark, Essex county, New Jersey, have invented certain new and useful Improvements in Sheet Feeding Mechanisms, of which the following is a specification.

This invention relates to sheet feeding mechanisms for printing or other machines and the object of the invention is to provide simple and effective means for automatically conveying a sheet on to the platen or similar part of a machine and automatically delivering the printed sheet.

In connection with this mechanism my invention also provides novel means for registering the sheet on the platen.

Other objects will appear as the specification proceeds.

In the accompanying drawing I have shown my invention applied to a platen press of the type known as a job press, but it will be understood that my device may be used on other types of presses or machines.

In the said drawings Figure 1 is a side elevation of a platen press equipped with a sheet feeding mechanism embodying my invention, with details omitted. Fig. 2 is a perspective detail view of the feeding mechanism. Fig. 3 is a perspective detail view of the platen and the parts thereon. Fig. 4 is a sectional view of the registering means taken on line 4-4 of Fig. 3, and Fig. 5 is a detail view of the blanket mechanism. Fig. 6 is a detail view of the registering mechanism.

In the said drawings the reference number 1 denotes the frame of the press, 2 is the platen, 3 the form carrying member, 4 the inking mechanism and 5 the ink table. These parts of the press are of the usual and well known form, and are in no wise changed in this instance. The platen and form member are oscillated in the usual manner and I have not deemed it necessary to enter into a detailed description or illustration of these elements.

My invention comprises the following elements: a mechanism for conveying the sheets onto the platen and automatically operated means on the latter for registering and holding the sheet while printing and also for delivering the printed sheet. The

rest of these two mechanisms is fully illustrated in Fig. 2, in which is shown two side brackets 6 joined by the two shafts 7 and 8 and the feed table 9. These brackets are suitably fastened to the frame and on 60 and between them is carried the conveying mechanism. The shaft 8 carries supporting fingers 10 and side guides 11, and on shaft 1 the stops 12 are fastened. The fingers, side guides and stops are all provided with 65 set screws and thus capable of transverse adjustment on the shafts to suit the sizes of the sheets. On the studs 13 screwed into the brackets on both sides slide the two guides 14 by means of slots 15, and in the 70 guides and movable therewith is the transverse slotted bar 16, which carries strips 17 which support the kickers 18. These latter serve to kick the sheet onto the platen and are adjustable lengthwise on the strips 17 75 and held by friction. The shaft 7 is given a slight rocking motion by means of arm 19, link 20, lever 21 carrying cam roll 22 co-acting with the platen locking cam 23. This latter normally belongs to the press and 80 serves to lock the platen in printing position and its operation is well understood. Inside the brackets the shaft 7 carries arms 24 by means of which the guides 14 are 85 moved. The shaft 8 is also given a slight rocking motion by means of arm 25 and link 26 which latter is also connected to lever 21 pivoted at 27. A spring 28 keeps the roll 22 on the cam.

On the platen at its front edge are screwed 90 two brackets 29, see Fig. 3, in which is journaled a roller 30 and on the one end thereof is provided a sheave 31 around which is wound a tape 32 which inner end is made fast to the sheave, so that by pulling 95 on the tape the roller 30 is rotated; a guard 33 prevents the tape from leaving the sheave. The roller 30 is provided with a slot 34 in which is inserted the one end of a blanket 35 and small points 60 are driven 100 in at the upper end of the slot and serve as hooks to retain the blanket, which is made of linen, silk, muslin or other suitable material. The opposite end of the blanket is 105 suitably fastened to a roller 36 which is 110 journaled in brackets 54 similar to the brackets 29 and fastened to the rear edge of the platen. A spring 37 is provided on roller 36 to keep the blanket taut and exerts a constant pull on the same toward the rear 115

edge of the platen. The ends 55 of the rollers 36 and 30 are provided with a right hand and a left hand thread between the brackets 54 and 29 and the ends of the 5 rollers, and nuts 56 are adapted to be fastened by screws 57 to the brackets 54 and 29 and to engage either the left or the right hand threaded portion of the ends of shafts 53. So that, as the blanket is moved on 10 the platen the rollers 36 and 30 will move sidewise to either the left or the right side, thus side registering the edge of the sheet to be printed against the fixed side register guides 42 which will be described in the 15 following. As shown in Fig. 6 when the blanket is operated the rollers 36 and 30 will be carried to the left and that side of the sheet registered. The one nut 56 is shown in dotted lines as only one at a time 20 will be used. In Fig. 3 these parts are omitted.

A rod 38 is held in the brackets 29 by thumb screws 39 and on this rod is supported brackets 40 by thumb screws 41. 25 The brackets 40 carry the side registering guides 42 screwed fast on the brackets 40 and on these guides are carried the top guides 43 the forward ends 44 of which are bent upward. A thin strip of suitable 30 material 45 is fastened under the guides 42 so that ways 46 are formed on either side between the strip 45 at the bottom, guides 42 on the side and top guides 43. This is clearly shown in Fig. 4. The top guides 35 43 are fastened at one point 47 and are capable of a slight up and down motion to which end they are preferably made of resilient material. Springs as 48 are also carried by the side guides 42 and have a 40 tongue 49 of about the same width as the top guides 43. The side guides 42 are slotted as indicated at 50 and through the slots extend the ends of the bent rods 51 which carry stops 52. The rods 51 are ad- 45 justably carried by the brackets 40 as shown. On the inking mechanism 4 is provided a hook 53 to which the free end of the tape 32 is attached.

The parts above described are easily at- 50 tached to the press by bolting on the two brackets 6 for the conveying mechanism, the brackets 29 and 54 to the platen and the hook 53 to the inking mechanism.

In making the press ready the thumb 55 screws 41 are loosened and the brackets 40 are swung upward, the blanket is then detached from the roller 30, the surface of the platen made ready and the operator can prepare for the printing. When the parts 60 are replaced and the press started the opera- 65 tion is as follows: A pile of sheets is placed on the table 9 and the single sheet is fed by hand on to the fingers 10 and against the stops 12, which at that time rest upon said fingers and the cam roll 22 is on the

high part of the cam 23. The kickers 17 will be so adjusted that the sheet falls between them and the stops. When the roll drops upon the low part of the cam the shaft 7 is rocked upwardly and the shaft 8 70 rocked downwardly to the left as seen in Fig. 2 with the result that the stops 12 are lifted, the fingers 10 are lowered slightly, the guides 14 move downwardly to the left and the kickers 17 kick the sheet rearwardly 75 on to the blanket 35, the sheet being side guided by the guides 11 and fed under the portions 44 of the top guides 43. At this time the hook 53 on the inking rollers move upward, the tape 32 is slackened and by 80 the action of the spring 37 the blanket is pulled rearwardly carrying the sheet with it rearwardly and to the one side until the sheet reaches the stops 52, the edges of the sheet being guided in the ways 46, and the 85 perfect side register being obtained by the shafts 55 engaging either the left or right hand threaded nut 56. The platen now moves down into printing position and when the impression is made the form member 90 acts on the springs 48 which in turn de- 95 presses the top guides 43 to hold the sheet firmly while the impression is on and strip the sheet from the form when the latter moves rearwardly. While this takes place 95 the tape 32 is slack as shown in dotted lines in Fig. 1. On the return stroke of the platen and just before the next sheet is kicked on to the blanket, the roller 30 is rotated by the tape 32 being pulled taut as 100 shown in full lines in Fig. 1 and thus the blanket is moved against the pull of the spring 37 and the printed sheet is carried out under the fingers 10 and delivered in the box 55a. The hook 53 now moves up- 105 ward again and the next sheet is carried into position on the platen.

The above is thought to clearly describe and illustrate the construction and opera- 110 tion of my device and it has been found that the same will operate quickly and satisfactorily. Changes may of course be made and I do not wish to be limited to the exact structure shown.

I claim—

1. In a printing or other machine a movable platen, a platen locking cam and an inking mechanism in combination with a blanket for moving a sheet on and off the platen, means for operating the said blanket 120 from the said inking mechanism, a conveying mechanism for conveying a sheet unto the said blanket and means for operating the said conveying mechanism from the said platen locking cam.

2. In a printing or other machine the combination of a movable platen, rollers mounted on and at the front and rear edges of said platen, a blanket carried by said rollers and operated thereby to carry a sheet 130

into printing position and deliver the printed sheet and means for moving one of said rollers longitudinally to register said sheet.

- 5 3. In a printing or other machine having a movable platen and a platen locking cam, the combination of a feeding mechanism, means for operating the latter from the said locking cam, a blanket, means for supporting the same on the said platen and 10 means for operating the said blanket to re-

ceive a sheet from the said feeding mechanism to carry the said sheet into printing position and means for operating said blanket to register the said sheet. 15

Signed at Newark, N. J., this 7th day of July, 1908.

LEWIS E. MORRISON.
